WHEEL COVER

William J. Flajole, Birmingham, Mich.

Application April 24, 1953, Serial No. 24,663

Term of patent 14 years

(Cl. D14—30)

To all whom it may concern:

Be it known that William J. Flajole, a citizen of the United States of America and a resident of Birmingham, in the county of Oakland and State of Michigan, has invented a new, original, and ornamental Design for a Wheel Cover, of which the following is a specification, reference being had to the accompanying drawing, forming a part thereof, and wherein:

Fig. 1 is a perspective view of a wheel cover showing my new design; and

Fig. 2 is a sectional view thereof.

The conventional tire and wheel assembly disclosed in dotted lines are shown only for the purpose of illustration.

I claim:

The ornamental design for a wheel cover, substantially as shown and described.
